UNITED STATES PATENT OFFICE.

HELION D. HARDENSTEIN, OF OKLAHOMA CITY, OKLAHOMA.

GAME.

Refile for abandoned application Serial No. 529,259, filed January 14, 1922. This application filed January 30, 1928. Serial No. 250,658.

This invention relates to new and useful improvements in amusing and instructive games, this application being refiled for abandoned application 529,259, filed Jan. 14, 5 1922.

The primary object of the invention is the provision of a game including a plurality of cooperating elements, each of said elements having delineations thereon, and 10 which elements are adapted for progressive arrangement by matching of delineations thereon, to produce special combinations of delineations.

A further object of the invention is the provision of a game of the above described character, which is of educational value, in that the delineations upon the blocks or elements are preferably numerical in designation, and adapted for arrangement in combinations to produce a desired resultant, thereby stimulating mental calculation by reason of the skill required to effect a desired resultant.

Other objects and advantages will be apparent during the course of the following detailed description.

In the accompanying drawings, forming a part of this specification, and in which similar reference characters designate corresponding parts throughout the several views.

Figure 1 is a plan view of a plurality of the various elements comprising an entire playing set, subdivided into groups A, B, C, 35 D, E, and F, for convenience.

Figure 2 is a perspective view of a block or element of this invention.

Figure 3 is a plan view of one of the improved game blocks.

Figure 4 is a plan view of the improved block illustrated in Figure 3 and showing an additional block in progressive playing arrangement therewith.

Figure 5 is a plan view of the improved blocks illustrated in Figure 4 and showing an additional block in progressive playing arrangement therewith.

Figure 6 is a plan view of the blocks illustrated in Figure 5, and showing an additional block in progressive playing arrangement therewith.

Figure 7 is a plan view of the improved blocks illustrated in Figure 6, and showing

an additional block in progressive playing arrangement therewith. 55

Figure 8 is a plan view of the improved blocks illustrated in Figure 7 and showing an additional block in progressive playing arrangement therewith.

Figure 9 is a perspective view of a filler block, used in guiding the playing arrangement of the blocks. 60

Figure 10 is a plan view of a playing arrangement of the blocks, showing the use of the filler element in connection therewith. 65

In the drawings, wherein for the purpose of illustration is shown a preferred embodiment of my invention, the letter G designates the improved playing elements or blocks of the invention, and which blocks G are 70 classified according to the spaces and delineations thereon, into "quadruples" H and "quads" K.

The blocks G are uniform in shape and size and are preferably square, the corners being 75 bevelled or cut away as at 10, to facilitate use of the blocks in playing formation. The blocks G are preferably of such standard size as to be one and one-half inches square in plan or horizontal dimension, and three-eighths of an inch in thickness. This arrangement, of course, need not be adhered to, since the blocks are susceptible to various polygonal formations. The face 11 of a block G is preferably divided into equal 80 spaces 12, by the diagonal intersecting lines 13 and 14, which extend from diagonal corners 10 of the block. The spaces 12 are thus substantially triangular in formation, and having a side 15 as a base for each of said 85 triangular spaces 12.

The "quadruples" H preferably total 10 in number, and each block or "quadruple" H is provided with a symmetrical arrangement of like delineations in each of its spaces 90 12. The delineations 16 which appear on the "quadruples" correspond to the different suits used in the playing of the game, and may be of any type of designation, although the same preferably have reference to numerical figures. Thus the first or lowest suit appearing on the "quadruple" would be indicated by the block or "quadruple" 17 in which the spaces 12 are preferably left blank, or might be delineated by the zero mark. The lowest counting suit would be 100 105

indicated by the "quadruple" 18 which is provided in each of the spaces 12 by the numerical character 1. The next highest "quadruple" would be indicated by the block 19, which would have the numeral 2 to indicate the delineation 16 in each of its spaces 12. This arrangement is continued in consecutive order to the last "quadruple" 26, and in each space 12 of which "quadruple" 26, the delineation 16, would take the form of the numeral 9.

The "quads" K are of course identical in size and formation to the "quadruples" H, and are provided with the spaces 12 upon their respective faces. The "quads" are preferably twenty in number, and thus total twice as many as the "quadruples" H. The 20 "quads" K are subdivided for classification purposes into five groups B, C, D, E, 20 and F, each group containing 4 blocks as indicated in Figure 1.

The delineation 27 in the various spaces 12 of the "quads" K, refer to the suits as indicated by the delineations 16 on the "quadruples" H. Each block of group B is provided with a blank space 12, in which no delineation appears; and having an opposite space 12 with the numeral 9 as its delineation 27. The remaining spaces of the 30 blocks in the group B have numerals 1 to 8 inclusive therein, appearing but once, representing the suits and to the exclusion of the numeral 9, which occupies an adjacent space 12. In the arrangement of numerals 1 to 35 8 inclusive, the odd numerals are placed opposite odd numerals, and even numerals opposite even numerals.

In group C, the order is somewhat similar. Each block of group C is provided 40 with a space 12 having a numeral 1 therein, and an opposite space 12 with the numeral 8 therein. The remaining spaces 12 of the blocks in the group being occupied by the delineations representing the suits of the game, to the exclusion of the suits 1 and 8, which appear on each block; and in the order above set forth for group B, i. e., with odd suits opposite odd, and vice versa.

Following the above system, each block 50 of group D is provided with oppositely placed numerals 2 and 7; group E with oppositely placed numerals 3 and 6; and group F with oppositely placed numerals 4 and 5; the remaining spaces of the various group 55 blocks having suits represented therein in the arrangement above set forth, and as illustrated in Figure 1.

From the foregoing, it can be seen that in each group of "quads", each block is provided with two directly opposite delineations or blank spaces 12, which when added will produce a resultant, which will be a common resultant for each "quad" block K, and which in this game will be 9. In this arrangement, each of the ten suits of the game

is represented eight times in the spaces of eight different "quads" K. This classification of numerals will greatly assist a player to become skilled. The classification of the "quadruples" H, is of course easy to remember, and requires very little mental effort. One-half of the spaces of the "quads" K can likewise be readily remembered, due to the placing of like delineations in each group, which go to make a common resultant for each "quad" block K. The remaining one-half of the spaces in the "quads" K, are not so easily remembered, but mental effort is somewhat stimulated, by cognizance of the fact that odd numerals are placed after odd, 75 and vice versa.

In starting the game, the entire set of thirty blocks comprising ten "quadruples" and twenty "quads" are placed face down upon a table or the surface upon which the game is to be placed, shuffled together, and the same divided according to the number of players. If two, three or four persons are playing, seven of the blocks G are given to each, and the remaining blocks are pushed aside to form a reserve, which reserve is to be drawn from when a player is unable to play.

The specific object of the game is to acquire a score of 250 or 500 points, by the 95 addition of successive combinations of delineations or numerals which the player is able to scheme by matching of delineations indicating a similar suit, and which will be subsequently set forth.

For clearness in the preferred manner of playing the improved game, several basic rules are to be followed, and are as follows:

Rule #1.—The starting player may place any "quad" or "quadruple" in his or her hand face up upon the playing surface, and the delineations thereon are counted. The second player may chose any space on this block for matching with one of his "quads" or "quadruples"; and the unmatched delineations of both blocks will be added to find a score for the 2nd player. Succeeding players may only match delineations or spaces directly opposite "dead" (matched) delineations or spaces (exception rule 3). 110

Rule #2.—When two opposite spaces or delineations of a "quad" have been properly matched, this "quad" is "dead" and cannot be used for further matching or counting purposes (exception rule #3). 120

Rule #3.—The first "quadruple" played is called a "spinner," and its four spaces or delineations are open for matching at any time. A player may match either space or delineation of the "spinner" adjacent its already matched spaces or delineations, and irrespective of an opposite open space or delineation. When two opposite spaces or delineations of a "spinner" have been matched, the remaining open delineations cannot be 130

used for counting, but may be used for matching.

Rule #4.—Points are only counted when the total of numerals as defined by the above 5 rules is a multiple of 5.

Several of the "quads" and "quadruples" have numerals in their spaces 12, the total of which is a multiple of five and these blocks are designated as counters. Thus the 10 "quadruple" 22 which designates the suit 5, and which is provided with a numeral 5 in each of its spaces 12, and the total of which numerals would equal 20, is a counter. There are four "quads" K in which the delineations 27 will total to a multiple of five, and by way of example a "quad" 35 which is provided with the numerals 2, 1, 7, 5, and which numerals total to 15, a multiple of 5, is a counter.

20 The progressive manner of playing the game has been illustrated in Figures 3 to 8 inclusive, and the order of which playing will now be described in detail. The first player plays a "quad" 36, in which the delineations or numerals are 1, 7, 8, 9, and which total 25, a multiple of 5, and consequently which total is recorded by a score keeper in favor of the first player. The second player prefers to play a "quad" 37 as 25 illustrated in Figure 4 of the drawings, and which "quad" 37 has the numerals 6, 9, 8 thereon. The numeral 9 of "quad" 37 matching numeral 9 of "quad" 36. The total thus secured by the second player is thirty 35 points, this total being obtained by counting the numerals in unmatched spaces 12 to the exclusion of the matched numerals 9. The score keeper records this thirty points in favor of the second player.

40 The third player prefers to play a "quadruple" 24 in which the suit 7 is represented, one of the 7's appearing in the space 12 of this "quadruple" 24 must match the 7 of the "quad" 36. Counting the portion for the 45 third player in accordance with the rules above set forth, said player is found to have secured a total of 35 points, and which are recorded by the score keeper in favor of this player. Attention is called to the fact that 50 the "quadruple" 24 played according to rule #3 of the game is the first quadruple and consequently a "spinner" and subject to the conditions mentioned in this rule. The fourth player is permitted to play upon any 55 space left open on the "spinner" or can play upon the blank space 12 of the "quad" 37, said player being precluded from playing in any other space of this block 37 or of the block 36 according to rule #2.

60 Player #4 prefers to play a "quad" 38 having the numerals 4, 3, 5, 7 thereon; the numeral 7 of this "quad" matches a numeral 7 of the "quadruple" 24 adjacent the already matched numeral 7 of this "quadruple".

65 The total of points for the fourth player, as

designated by the rules is 40, and is recorded by the score keeper. Should player #4 have played this "quad" 38 directly opposite the "quad" 36, he would have been precluded from counting the open unmatched delineations of "quadruple" 24, according to rule #3.

70 Player #5, or the next player according to the number of players in the game prefers to play a "quad" 39 having the numerals 2, 4, 7, 8 thereon, and upon the "quadruple" 24 opposite the "quad" 38. This gives player #5 a total of 40 points. The succeeding play, as illustrated in Figure 8, is performed by the addition of a "quad" 40 to the single 75 unmatched space of the "quadruple" 24. The total secured by this player is 48 points, and the same not being a multiple of 5, cannot be recorded by the score keeper in favor of this player. The game is continued in 80 this manner until one of the players exhausts his or her supply of "quads" or "quadruples", and at which point in progress of the game, the player having no more of the blocks with which to play will inform the 85 remaining players. The remaining players will then turn the "quads" and "quadruples" face up and count their respective points. The score keeper will then credit the player first exhausted of blocks with the total of 90 95 that player whose remaining blocks total nearest a multiple of five.

95 The "quads" and "quadruples" are then turned face down, shuffled again, and the game is progressively played as above described, until one of the players secures a score, such as 250 or 500 points, thus winning the game.

100 A filler block L is provided, substantially triangular in formation, having sides 42 and 43, of the same length as the sides 15 of the blocks G. The sides 42 and 43 are preferably at right angles to each other having an opposite hypotenuse side 43^a, the points of juncture of the sides 42 and 43, with the side 43^a being bevelled as at 44. The top or face 45 of the filler block L is preferably provided with an arcuate indicating mark 46, in the present instance a doubled headed arrow point toward the sides 42 and 43. 110 115 This filler block L is provided to facilitate playing of the game.

120 The game will ordinarily be played upon some supporting surface M such as a table, and the length and dimensions of which are ordinarily limited. It will not, at all times, be convenient to arrange the blocks G upon the top of the table M, in such manner that the game will be played to a finish, without any liability of the blocks running off the 125 edge of the table element M. In order that the progressive playing may proceed without determination of a line of play, as by said line of play reaching the end of the table, the filler elements L have been pro- 130

vided to shift the direction of the line of play, thus keeping the sequence of said line of play upon the table top, and readily discernible by the players. As shown in Figure 10, the blocks G have been played toward an end of the player M, and the line of play has been changed at right angles to the original line of play. This change of direction is obtained by abutting the bevelled edges 10 of a pair of blocks G. In this position, the abutting blocks G will be unfinished in appearance and liable to lead to confusion, if no indication of the change of direction is readily seen, and will be liable to mislead a player. Therefore, the filler block L is inserted in order that its right angled edges 42 and 43 will contact with the adjacent edges 15 of the matched spaces 12 of blocks G. In this position, the arrow element 46 will indicate the change of direction, and serve as a ready indicator to that effect. This change of direction has been illustrated in Figure 10, by two of the fillers elements L showing the method of preventing the line of play from running off of a table.

A different method in the manner of playing the game can of course be devised, and the above described progressive system of playing need not be strictly followed.

Changes may be made to the shape, size and arrangement of parts upon the blocks G without departing from the spirit of the invention or the scope of the claims.

35 I claim:

1. A game comprising in combination a plurality of polygonal shaped blocks having a face of each quadrangularly spaced, a numerical delineation of varying suit in each space of said faces, the delineations of predetermined spaces of each block having a resultant common to similarly positioned delineations of each of the several blocks, and a block for each suit as determined by the

delineations of said first mentioned blocks, 45 said block of each suit having similar delineations of its respective suit thereon, all of said blocks adapted for progressive arrangement by matching delineations of different blocks to offset numerical calculations. 50

2. The combination of a plurality of blocks designated "quadruples", each of said "quadruples" having four similar delineations thereon indicating suits, and a plurality of blocks designated "quads", each of said "quads" having four dissimilar delineations thereon of the suits represented by said quadruples, said "quadruples" and "quads" adapted for progressive matching of similar delineations to effect a resultant. 55

3. In a game of the class described a plurality of playing blocks each having a plurality of numerically represented delineations thereon, with each delineation similarly represented on several of the blocks so that the blocks may be relatively positioned by matching similar delineations, the total resultant of certain predetermined positioned numerically represented delineations of any one block being a common resultant for similarly positioned but dissimilar numerically represented delineations of each of the several blocks. 65

4. A game comprising a plurality of playing elements having numerically represented indicia thereon corresponding to suits, said playing elements having several suits appearing on the same and adapted for progressive matching of similar suits to obtain a calculation, and a guiding element having 80 direction indicating indicia thereon adapted to be cooperatively positioned with said playing elements during playing of the game where a change has become necessary for correctly designating the matched delineations of the playing blocks at the point of change of playing direction. 85

HELIOT D. HARDENSTEIN.
